IGNITION CIRCUIT

William Oscar Kennington, London, England, assignor to General Motors Corporation, Detroit, Mich., a corporation of Delaware

Application February 16, 1934, Serial No. 711,473
In Great Britain January 25, 1933

3 Claims. (Cl. 123—148)

This invention relates to electrical coil ignition circuits of internal combustion engines.

The main object of the invention is to provide efficient ignition at high engine speeds.

5 More specifically the object is to reduce the time required, after closure of the circuit breaker, for the current flowing through the primary winding of the ignition coil to acquire an ample value.

The present invention consists of a relay having 10 a coil winding for connection in series with the main contact breaker, with the primary winding of the ignition coil and with a pair of its own contacts, a second coil winding and a resistance across said contacts, and a third polarizing winding, the relay being adapted to operate at a current value which is between that which is injurious to the primary coil and the minimum requisite for ignition.

An embodiment of the invention is illustrated 15 diagrammatically in the accompanying drawing.

In an ignition circuit, it is necessary for the current, when the main contact breaker breaks the circuit, to be of such a value that the spark in the secondary circuit is sufficient for ignition.

20 It is also necessary that this current be built up within the period between the make of the main contact breaker and the succeeding break. This period is inversely proportional to the speed of the engine. At high speeds, say from 4,000 R. P. M. upwards, therefore the period may become so short that the primary current cannot build up to the requisite value. The time taken by the

25 current to build up from zero varies as a function of the applied voltage. Ignition can therefore be obtained at high speeds by using a relatively high voltage. With such a voltage, however, excessive current flows through the primary coil when the engine is running at low speeds.

30 A resistance inserted in the circuit will cut down this current to a value which is not injurious to the ignition coil.

Referring now to the accompanying drawing, there is shown a battery *a*, and ignition coil with primary and secondary windings *b* and *c* respectively, and a main contact breaker *d* with its associated condenser *e*. In series with the primary winding *b* and the contact breaker *d* is a current coil *f* of the relay whose armature contacts *g* are also in the same series circuit. Across the contacts *g* is a holding coil *h* and a resistance *j* in series with one another. The contacts *g* are normally held closed by a spring *k*. In a parallel circuit, connected across the battery, is a third coil *l* of the relay, this being a voltage or polarizing coil. The coil carries a constant current when

the circuit is completed through the main ignition switch *m*.

The ampere turns of the coils *h* and *l* should be approximately equal, although the latter coil is naturally a high resistance coil passing very little current, say something of the order of about 40 to 50 milliamperes, since it is always in circuit with the battery *a* when the ignition switch *m* is on. These three coils and the spring *k* are arranged so that when the circuit is closed through *d*, the contacts *g* are opened as soon as the current through the circuit *a*, *b*, *f*, *g*, *d* reaches a value which is injurious to the coil *b*. For example, when a battery of 12 volts is used with an ignition coil designed for a 6 volt circuit, the current should not exceed about 4 amperes. In such an arrangement the relay can be made to operate effectively so that it will just open the contacts at a total value of about 300 ampere turns. Once the contacts *g* are open, coils *l* and *h* keep them 60 open until the current falls below a value which is slightly less than the above mentioned operating value, whereupon the spring *k* closes the contacts. This occurs of course when the main contact breaker *d* breaks the circuit, the relay operating in 65 step with the main contact breaker. The total resistance of coils *f* and *h* and resistance *j* should be such that for a current value existing when the contacts *g* are open, the voltage drop across the same is equal to the difference between the 70 applied voltage and that for which the induction coil is designed.

75 It will thus be seen that the device automatically limits the primary current to a value which is below that which is injurious to the primary 80 coil and above the minimum which produces a sparking voltage.

85 At low engine speeds the current has time to build up to at least the minimum for ignition, before the main contact breaker *d* breaks the 90 circuit. The relay however, prevents the current reaching an excessive value. At high engine speeds, the current, due to the excess applied voltage, still builds up quickly enough to a value sufficient for ignition purposes. Speeds as high 95 as 10,000 and even 12,000 R. P. M. are possible by the application of this invention. The limiting speed at which sparking fails is reached when the time between a make and break in the primary circuit is just less than the time required 100 for the current to build up to the minimum value for ignition purposes. The pull-up time, or time lag of the relay is in excess of this build up time, so that at the highest speeds, say above 4,000 105 R. P. M. it does not operate: the contacts re- 110

main closed. The full voltage of the battery *a* is then used across the circuit. The pull-up time of the relay may of course be varied; for example, by adjusting the spring *k*. It will be seen that 5 the operating value of the relay current is above the minimum required for ignition purposes, but below that which becomes injurious to the primary coil.

The voltage or polarizing coil *l* allows less 10 ampere turns to be used on coil *f* and this reduces the impedance of the circuit. It also produces some initial magnetism in the laminated core of the relay and thus reduces the work and time required for the current in coil *f* to open the 15 contacts *g*. An alternative to this coil *l* is to give the laminated core of the relay a certain degree of residual magnetism.

Should the voltage of battery *a* fall below a certain value such as 6 volts, for example during 20 the operation of a starting motor, the system operates as a normal ignition system, for the contacts *g* remain closed.

To obtain a quick break, the movable contact of the pair *g* can be resiliently mounted on the 25 relay armature the arrangement being such that when the latter has acquired its full momentum, a lug on it pulls down the contact arm to open the circuit.

It is to be understood that no limitation of the 30 scope of the invention is to be implied from or effected by the figures and values given above since these may be varied to suit any particular practical requirements that may have to be fulfilled.

35 What I claim is:—

1. A current limiting device for coil ignition systems of internal combustion engines compris-

ing a relay having a coil winding for connection in series with the main contact breaker, with the primary winding of the ignition coil and with a pair of its own contacts, a second coil winding and a resistance across said contacts, and a third polarizing winding, the relay being adapted to operate at a current value which is between that which is injurious to the primary coil and the minimum requisite for ignition. 80

2. An ignition system for an internal combustion engine comprising in series an ignition coil, a battery which is of higher voltage than that for which the coil is designed, a main contact breaker, and one coil and the armature contacts of a relay, said contacts being shunted by a second relay coil and a resistance whose combined ohmic resistance when in circuit cuts down the voltage across the ignition coil to its designed value, a third coil of said relay being connected across said battery, said relay being designed to open its contacts at a current value therethrough slightly above that requisite for ignition. 85 90 95

3. A current limiting device for coil ignition systems of internal combustion engines comprising a relay having a coil winding for connection in series with the main contact breaker, with the primary winding of the ignition coil and with a pair of its own contacts, a second coil winding and a resistance across said contacts, the initial magnetism of the core of the relay being such 100 105 110 115 that the current through said first coil winding operates said relay when it reaches a value which is injurious to the primary coil, so that said second coil winding and resistance are inserted in the primary circuit. 120
